UNITED STATES PATENT OFFICE

WILLIAM D. ANTRIM, OF GLOUCESTER, NEW JERSEY, ASSIGNOR TO ROBERTS & MANDER STOVE COMPANY, OF PHILADELPHIA, PENNSYLVANIA, A CORPORATION OF PENNSYLVANIA

DESIGN FOR A GAS RANGE GRID

Application filed January 25, 1933. Serial No. 46,973. Term of patent 7 years.

To all whom it may concern:

Be it known that I, WILLIAM D. ANTRIM, a citizen of the United States, residing in Gloucester, Camden County, New Jersey, and have invented a new, original, and ornamental Design for a Gas Range Grid, of which the following is a specification, reference being had to the accompanying drawing, forming part thereof, in which:

Fig. 1 is a perspective view of a gas range grid illustrating my new design;

Fig. 2 is a section on the line 2—2, Fig. 1;

Fig. 3 is a section on the line 3—3, Fig. 1.
I claim:

The ornamental design for a gas range grid, substantially as shown.

WILLIAM D. ANTRIM.
